(57) **CLAIM**

The ornamental design for a sneaker with a leg cover, as shown and described.

DESCRIPTION

FIG. 1 is a front perspective view of a sneaker with leg cover showing my new design;

FIG. 2 is a first side view thereof;

FIG. 3 is a second side view thereof;

FIG. 4 is a back view thereof;

FIG. 5 is a front view thereof;

FIG. 6 is a top view thereof;

FIG. 7 is a bottom view thereof;

FIG. 8 is a back view thereof shown in an unzipped configuration;

FIG. 9 is a front view thereof shown in an unzipped configuration;

FIG. 10 is a back view thereof shown in a wide-open unzipped configuration;

FIG. 11 is a front view thereof shown in a wide-open unzipped configuration;

FIG. 12 is an exploded front perspective view thereof;

FIG. 13 is an exploded first side view thereof;

FIG. 14 is an exploded second side view thereof;

FIG. 15 is an exploded back view thereof;

FIG. 16 is an exploded front view thereof;

FIG. 17 is an exploded back view thereof shown in an unzipped configuration; and,

FIG. 18 is an exploded front view thereof shown in an unzipped configuration.
